UNITED STATES PATENT OFFICE.

ROMAN B. MALISZEWSKI, OF MILWAUKEE, WISCONSIN.

AEROPLANE.

Application filed April 16, 1928. Serial No. 270,360.

This invention relates to aeroplanes, and is particularly directed to the bracing of the wings of aeroplanes.

- Objects of this invention are to provide a 5 novel form of wing bracing for aeroplanes, which is so constructed that it will take the forward or backward thrust of the wings, and which maintains the angle of incidence with absolute accuracy.
- 10 Further objects of this invention are to provide a wing bracing construction which minimizes the air resistance and which reduces the number of props or struts, or wires required for the wings of aeroplanes.

- 15 Further objects of this invention are to provide a wing bracing construction which provides additional strength for the portions of the wing, and which is so made that a single prop or strut may be employed for 20 each wing and may be secured to the wing along the line through the center of lift of the wing.

A further object is to provide a novel form 25 of aeroplane construction, in which the vision of the occupants is not obstructed by the props or struts for supporting the wings.

Further objects are to provide an aeroplane construction which will securely brace the wing in a novel and highly efficacious 30 manner, and which is relatively simple, is of light weight, and may be easily applied.

An embodiment of the invention is shown in the accompanying drawings in which:

Figure 1 is a plan view of the portion of 35 an aeroplane with parts broken away showing the bracing in place;

Figure 2 is a sectional view on the line 2—2 of Figure 1.

Referring to the drawings, it will be seen 40 that a monoplane has been chosen for illustration. The fuselage has been indicated by the reference character 1 and one of the wings by the reference character 2. These wings are provided with a forward beam 3 and a 45 rear beam 4. They are also equipped with a forward strip 5 and a rear strip 6, although the beams 3 and 4 take the major strain of the wing. Although the cross bracing transversely of the wing has been omitted 50 from the drawing for the sake of clearness, it is to be understood that this cross bracing is employed in the usual manner.

These wings are ordinarily braced from 55 the fuselage merely by two lower struts. These struts, however, do not offer any resist-

ance to forwardly or rearwardly directed thrust exerted upon the wing.

In order to take care of the forward and rearward thrust, a diagonal bracing member 7 extends from the rear portion of the fuselage 1 to each of the wings. The diagonal bracing member 7 may be secured to the fuselage in any suitable manner, as by means of the socket bearing 8, shown in Figures 1 and 2. This bracing may be of wood, metal, or other suitable material. It extends, as is apparent from Figure 2, across the rear beam 4 and beneath the forward beam 3. It is secured to each of these beams in a rigid manner. An auxiliary brace 9 crosses the main 70 brace 7 and is secured to the upper side of the rear beam 4 and the lower side of the forward beam 3. These braces are arranged to cross at the center line of lift and a single strut or prop 10 extends from the lower portion of the fuselage to this point of crossing and is secured to these braces at their point of crossing.

Thus, a single strut or prop is employed and is directly attached to the wing along the center line of lift.

Further, it will be seen that the diagonal main brace 7 securely braces the wing against rearward or forward pressure and also maintains the angle of incidence unvarying. The 85 addition of the auxiliary brace 9 produces the effect as if the main brace 7 were attached at more than two points to the forward and rearward beams 3 and 4, and thus increases materially the rigidity of the structure. The 90 cross braces also aid in preventing lateral distortion of the wing.

It is to be noted, also, that the main brace 7 when positioned as shown, together with the prop 10, permits a wing bracing that 95 offers less air resistance in comparison with other external types of wing bracing.

It is to be understood that although the brace has been shown as extending rearwardly, it may extend forwardly under certain conditions, and that although the strut or prop 10 has been shown as extending downwardly, it may extend upwardly under certain conditions.

Although the invention has been described in considerable detail, such description is intended as illustrative rather than limiting, as the invention may be variously embodied and as the scope of such invention is to be determined as claimed.

I claim:

1. An aeroplane comprising a fuselage wings projecting therefrom, diagonal braces extending from a rear portion of the fuselage forwardly and outwardly and attached to the wings, and a strut extending upwardly from the lower portion of the fuselage beneath the wing to each of the diagonal braces.
2. An aeroplane comprising a fuselage, a pair of wings projecting therefrom, a main diagonal brace for each of said wings, said brace extending from a rear portion of the fuselage into the wing and forming a diagonal thrust receiving brace to reinforce the wing against lateral thrust either directly forwardly or rearwardly, and an auxiliary diagonal brace secured to said first mentioned diagonal brace and extending transversely thereto and attached to the wing.
3. An aeroplane comprising a fuselage having a pair of outwardly projecting wings, each of said wings being provided with a front and a rear beam, a diagonal main brace for each of said wings, said diagonal brace being secured adjacent a rear portion of the fuselage behind the wing and extending across the forward and rear beams and secured thereto, and a strut extending upwardly from beneath the wing and secured at one end to the fuselage and at the other end to the diagonal brace.
4. An aeroplane comprising a fuselage having outwardly projecting wings, each of said wings being provided with a front beam and a rear beam, a main diagonal brace for each of said wings secured to a rear portion of the fuselage and extending outwardly and forwardly and positioned immediately behind the wing, said brace extending across the front and rear beams and attached thereto, an auxiliary diagonal brace extending across the front and rear beams and terminating adjacent said beams and secured to said main diagonal brace, and a strut extending upwardly from the fuselage beneath the wing and secured to said braces at their point of crossing.
5. An aeroplane comprising a fuselage, a pair of outwardly projecting wings, each of said wings having a forward beam and a rearward beam, a diagonal main brace for each of said wings secured to a rear portion of the fuselage and extending over the rear beam and beneath the forward beam and attached to each of said beams, an auxiliary diagonal brace for each of the wings secured to each of said beams and to said main beam, and a strut positioned below the wing and extending upwardly from the lower portion of the fuselage and secured to the point of crossing of said main and auxiliary braces, said point of crossing being at the center line of lift of the wing.

In testimony that I claim the foregoing I have hereunto set my hand at Milwaukee, in the county of Milwaukee and State of Wisconsin.

ROMAN B. MALISZEWSKI.
